DESIGN FOR A COMBINED BREAD AND BUTTER TRAY

Clarence Ray Snoke, Berkley, Mich.

Application April 13, 1945, Serial No. 118,972

Term of patent 7 years

(Cl. D44—10)

To all whom it may concern:

Be it known that I, Clarence R. Snoke, a citizen of the United States, residing at Berkley, in the county of Oakland and State of Michigan, have invented a new, original, and ornamental Design for a Combined Bread and Butter Tray, of which the following is a specification, reference being had to the accompanying drawing, forming a part thereof.

Figure 1 is a top plan view of a combined bread and butter tray, showing my new design;

Figure 2 is an edge view; and

Figure 3 is a sectional view thereof taken on the line 3—3 of Figure 1.

I claim:

The ornamental design for a combined bread and butter tray, as shown.

CLARENCE RAY SNOKE.
